UNITED STATES PATENT OFFICE.

THOMAS M. WOYTON, OF BROOKLYN, NEW YORK.

CLIP.

Application filed August 23, 1921. Serial No. 494,528.

To all whom it may concern:

Be it known that I, THOMAS M. WOYTON, a citizen of the United States, residing at Brooklyn, in the county of Kings and State 5 of New York, have invented certain new and useful Improvements in a Clip; and I do hereby declare the following to be a full, clear, and exact description of the invention, such as will enable others skilled in the art 10 to which it appertains to make and use the same.

The invention relates to a combined article and pocket clip, whereby a number of papers may be secured in compact form and fastened 15 to a pocket, garment or like part.

The invention consists of a dual clip comprising two opposed gripping members and an intermediate abutting member, the several parts being of peculiar construction and 20 arrangement.

Other objects and advantages will be apparent and suggest themselves as the nature of the invention is understood.

While the drawing illustrates an embodiment 25 of the invention it is to be understood that in adapting the same to meet different conditions and requirements, various changes in the form, proportion and minor details of construction may be resorted to without departing from the nature of the invention.

Referring to the accompanying drawing forming a part of the specification,

Figure 1 is an elevation of a clip embodying the invention,

Figure 2 is an edge view thereof, and

Figure 3 is a top view of the device.

Corresponding and like parts are referred to in the following description and designated in the several views of the drawing 40 by like reference characters.

The clip comprises an article grip 1, a pocket clip 2 and an intermediate abutting member 3 common to the two grips and co-acting therewith.

The article grip is formed preferably of a single length of wire of suitable gage having its opposite end portions bent laterally in the same direction to form a jaw 4 and an extension 5 and a retainer 6. The wire at a 45 point intermediate the lateral extension 5 and jaw 4 is formed into a coil 7 which gives added resiliency to admit of a relatively thick article being gripped between the parts 1 and 4. The jaw 4 consists of a 50 loop and projects some distance beyond the end of the lateral extension 5 to insure firm

and positive engagement with a packet of papers, a purse or other article to be made secure.

The pocket clip comprises the elements 2 and 3 which constitute parts of a single metal strip folded upon itself and receiving the lateral extension 5 in the fold. The free end of the part 3 engages the jaw 4 and is yieldingly held in contact therewith by 60 means of the retainer 6 which extends across the clip adjacent the bight or fold in which is located the lateral extension 5. The terminal portion of the retainer 6 is bent rearwardly to extend across the inner edge of 65 the pocket clip and prevent inward movement or displacement thereof. The retainer 6 consists of an end portion of the lateral extension 5. Outward displacement of the pocket clip is prevented by the portion of 70 the wire connecting the lateral extension 5 with the retainer 6. The retainer 6 exerts a degree of pressure on the pocket clip to yieldably hold the member 3 in engagement 75 with the jaw 4 whereby an article placed between the parts 3 and 4 will be firmly gripped in substantially the same manner as a clip of any formation. The blank from which the pocket clip is formed consists of 80 a strip of spring metal of any nature suitable for the purpose. The pocket clip 2 is offset as indicated at 9 to form an abutment or stop for the retainer 6 as well as to properly space the upper end of the part 2 from 85 the part 3.

In practice papers, letters, purses or other article to be made secure is held between the jaw 4 and abutting member 3 after which such articles are placed in the pocket and are made secure against displacement by gripping the upper portion of a side of a pocket between the member 3 and the part 2. It will thus be understood that the article cannot readily slip from the pocket when the person stoops or leans forward. Moreover, 100 the clip guards against the pocket being picked since a side of the pocket is firmly gripped between the elements 2 and 3 constituting the pocket clip.

Having thus described the invention, what I claim is:—

1. A clip comprising an element having a lateral extension at one end and a laterally extending jaw at the opposite end, a member mounted upon said lateral extension and 110 cooperating with the said jaw and a retainer forming a part of said lateral exten-

- sion and engaging the member mounted thereon to hold the same in operative position.
2. A clip comprising an element having a lateral extension at one end and a laterally extending jaw at the opposite end, a member mounted upon said lateral extension and cooperating with the said jaw and having an offstanding portion adjacent said lateral extension and a retainer engaging the offstanding portion of said member and exerting a pressure thereon to hold the parts in cooperative relation.
3. A clip comprising an element having a portion formed into a coil and having a lateral extension at one end and a laterally extending jaw at the opposite end and a member mounted upon said lateral extension and cooperating with the said jaw.
4. A clip comprising an element having a lateral extension at one end having an inwardly extending retainer with its terminal portion bent laterally and having a laterally extending jaw at its opposite end and a member mounted upon said lateral extension and held against displacement by said retainer and the bent terminal portion thereof, the opposite end portions of the member coacting with the said jaw to grip an article therebetween.
5. A dual clip comprising a metal strip

folded upon itself to form an abutting member and a pocket clip, and an element having a lateral extension at one end extending through the fold of the metal strip and having its end portion rebent to engage the clip adjacent the fold and said element having a laterally extending jaw at its opposite end to cooperate with the abutting member of the said clip.

6. A clip of the character specified comprising a wire having a portion formed into a coil and having a lateral extension and retainer at one end with the terminal portion of the retainer bent laterally and having a laterally extending jaw at its opposite end and a metal strip folded upon itself to provide an abutting member and a pocket clip, the fold of the strip receiving said lateral extension, and the pocket clip having an offset portion with which said retainer is in engagement, the bent terminal portion of the retainer engaging an edge of the pocket clip to prevent displacement of the same and the latter coacting with the said jaw.

In testimony whereof I affix my signature in presence of two witnesses.

THOMAS M. WOYTON.
